UNITED STATES PATENT OFFICE.

MICHAEL G. GRUNDMANN, OF FARIBAULT, MINNESOTA.

SHOE.

Application filed March 30, 1925. Serial No. 19,371.

This invention relates to shoes, one of its objects being to provide a structure wherein the lining is stitched in place separately from the upper, the box toe and the welt, the shoe 5 being smooth inside, light and flexible and being made either with or without an inner sole.

Another object is to provide a shoe in which the lining, etc., which are underneath 10 the upper, are fastened separately on a middle sole to which the upper is also attached, this middle sole and the welt being subsequently fastened to the outer sole.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed may be made within the scope of what is claimed without departing from the spirit of the invention.

In the accompanying drawings the preferred forms of the invention have been 25 shown.

In said drawings,

Figure 1 is a section through a portion of a last showing the first stage in the formation 30 of a shoe constructed in accordance with the present invention.

Figure 2 is a similar view showing a box toe secured in place with the lining.

Figure 3 is a view similar to Figure 2 showing 35 the upper secured to the middle sole.

Figure 4 is a view similar to Figure 3 showing the outer sole and the welt fastened to the middle sole.

Figure 5 is a section through a last and a 40 portion of a shoe formed with a single sole.

Figure 6 is another similar section showing a slightly modified form of shoe wherein the single sole is grooved.

Figure 7 is an enlarged section through a 45 portion of a modified form of single sole.

Figure 8 is a section similar to Figure 4 but showing a grooved middle sole for receiving the lining.

Referring to the figures by characters of 50 reference L designates a portion of a last on which the shoe is to be formed. In assembling the parts of the shoe the inner sole 1 and the middle sole 2 are fastened temporarily to the last means of nails N; the middle sole being arranged to extend outwardly 55 beyond the inner sole a sufficient distance to

receive the welt hereinafter mentioned. The lining 3 is then stretched over the last with an outturned edge portion 4 bearing on the middle sole, said lining being extended 60 against the edge of the inner sole. If a box toe 5 is used it is placed on the lining with its flange 6 extending outwardly and resting on the flange 4 as shown in Figure 2. The two flanges are then sewed together and to 65 the middle sole by stitches indicated at 7. The upper 8 is next applied and has its free edges outturned to provide a flange 9 resting on the middle sole beyond the edges of the flanges 4 and 6. A welt 10 is positioned 70 on the flange 9 but before this is done said flange is fastened to the middle sole by stitches indicated at 11. An outer sole 12 is applied to the outer face of the middle sole and the same stitches 13 which are used for 75 fastening the welt 10 in position are also extended through the flange 9 and through the middle sole and the outer sole for holding them all together.

Under some conditions the middle sole 80 can be formed with a groove 14 to receive the edge portion of the lining 15 as shown in Figure 8, thereby to render the shoe less bulky adjacent the welt than is the structure 85 shown in Figure 4.

Cheaper grades of shoes can be made with single soles as shown in Figures 5, 6 and 7. The single sole 15 can be formed with a slit 16 extending thereinto from its edges so as to provide a lip 17 which can be turned 90 down as indicated by broken lines. As shown in Figure 5 the lining 18 can be fastened directly to this sole 15 by stitches 19 extending to the slit 16 and if a box toe 19 is used the same stitches can be employed for 95 holding it in place. The upper 20 is fastened by stitches 21 extending through the edge portion of the upper and through sole 15 to slit 16. The lip 17 is then pressed back into place so as to close the slit 16 after 100 which all of the parts can be held together by stitches 21' extending through sole 15, lip 17 upper 20 and the welt 22. Instead of fastening the lining, etc., upon the flat top face of the sole 15 said sole can be channeled 105 as indicated at 23 to receive the edge portions of the lining, box toe and upper, thereby rendering the shoe less bulky in appearance. This channel can be cut at any desired angle and in Figure 7 the bottom of the 110 channel has been illustrated at 24 as inclined.

A shoe constructed as described is very

smooth inside, light and flexible and can be made easily.

If desired an inner sole 25 can be used with the shoe illustrated in Figure 5.

5. What is claimed is:

1. A shoe including middle sole and outer sole portions, a lining secured to the middle sole and having an outturned marginal portion terminating inwardly from the edge of the middle sole, an upper secured to the middle sole and having an outturned portion interposed between the edge of the lining and the outer edge of the middle sole, an inner sole upon the middle sole and having its edges abutting against the lining at its point of contact with the middle sole.

15 2. A shoe including middle sole and outer sole portions, a lining secured to the middle sole and having an outturned marginal

portion terminating inwardly from the edge 20 of the middle sole, an upper secured to the middle sole and having an outturned portion interposed between the edge of the lining and the outer edge of the middle sole, an inner sole upon the middle sole and having its 25 edges abutting against the lining at its point of contact with the middle sole, means extending through the middle sole for attaching the outturned portion of the lining and the outturned portion of the upper to the 30 middle sole, the marginal portion of the outer sole constituting means for concealing said attaching means.

In testimony that I claim the foregoing as my own, I have hereto affixed my signature.

MICHAEL G. GRUNDMANN.
